CENTRIFUGAL SEPARATOR

John Mann, Seneca Falls, N. Y., assignor to
Goulds Pumps, Inc., Seneca Falls, N. Y., a corporation of New York

Application April 26, 1934, Serial No. 722,463

12 Claims. (Cl. 233—19)

This invention relates to centrifugal separators.

The object of the invention is to provide a centrifugal separator which is simple in construction, economical to manufacture, efficient in operation, and which will effectively perform functions for which it is intended.

A further object is to prevent undesirable remixing of materials separated centrifugally.

A still further object is to provide a centrifugal separator adapted for a wide variety of operations.

Other objects of the invention will in part be obvious and will in part appear hereinafter.

The invention accordingly comprises the features of construction, combinations of elements, and arrangement of parts, which will be exemplified in the constructions hereinafter set forth and the scope of the application of which will be indicated in the claims.

For a fuller understanding of the nature and objects of the invention reference should be had to the following detailed description taken in connection with the accompanying drawing, in which:

Figure 1 is a vertical sectional view of a centrifugal separator embodying the invention;

Fig. 2 is a fragmentary vertical sectional view illustrating a modification.

In the usual type of centrifugal separator the lighter liquid is thrown out of the top of the separator member, and the heavier liquid is allowed to flow outwardly at a lower point. Commonly, the casing of the machine is formed with a flange which extends inwardly toward the neck of the separator member between the flows of separated liquids. In order to permit free rotation of the separator member, a clearance space is left between the neck and the flange. The rotation of the separator member tends to build up an increased pressure within the casing beneath the flange because of the centrifugal action of the exterior walls of the separator member. This pressure gives rise to an outflow through the exhaust pipe for the heavy liquid, with the result that there is a considerable compensating inflow of air through the clearance space. This inflow tends to carry with it the lighter liquid thrown off above the flange with consequent unsatisfactory results. When the lighter liquid is the end product sought, as in the separation of oil from water, this results in a considerable decrease in the yield, and when the heavy liquid is the end product sought, it results in the contamination of the heavy liquid. With the foregoing and other difficulties in view, the present invention con-

templates preventing the remixture of materials separated by a centrifugal separator, and in its exemplified embodiment, accomplishes this by controlling the pressure within the chamber so that there is no undesirable tendency for an air flow through the clearance space in an undesired direction.

In accordance with the invention there may be built up within the chamber about the separator member an air pressure such that a suitably limited air flow through the clearance space is caused in a desired direction or such that there is created a balanced pressure condition with no tendency for air to move through the clearance space in either direction.

As shown in Fig. 1, the exemplified embodiment of the invention comprises a separator member 9 rotatably carried on a standard 10 driven by a shaft 11. The material to be separated, such for instance as a mixture of oil and water, is introduced into the lower portion of the separator member through an axial conduit 12, ports 13, and passageway 14. The centrifugal action within the rotating member tends to cause the heavier material, e. g., water, to gather against the outer wall of the separator member, and the lighter material, e. g., oil, to build up nearer the axis of the separator member. An annular baffle 15 near the top of the separator member is provided to assure proper separation of the materials. The lighter liquid flows inside the baffle, through a passageway 16 disposed about the conduit 12, and upwardly through a neck portion 17 of the separator member, and is thrown outwardly at 18 at the top of this neck portion. The heavier liquid flows outside the baffle 15 at 19 and beneath an inwardly-extending portion 20 of the separator member, and out through an opening 21 at the base of the neck 17.

In order to preserve the ejected materials and assure their collection, there is provided a stationary casing 22 about the separator member. This casing includes a flange 23 which extends inwardly to a point adjacent the neck of the separator member beneath the openings 18 and above the openings 21. There is thus provided a chamber 24 for the reception of the lighter liquid, and a chamber 25 for the reception of the heavier liquid. The lighter liquid runs off through a pipe 26, and the heavier liquid runs off through a pipe 27 extending from a chamber portion 28 beneath the separator member. As will be noted, the standard 10 is of less diameter than the separator member.

In order to assure free rotation of the sepa-

rator member, a clearance opening, as indicated at 30, is left between the inner edge of the flange and the neck of the separator member. As will be seen the rotation of the body of the separator member tends to act as a pump to cause an air flow through this clearance space; and that such flow would tend to carry separated light liquid into the chamber 25. In order to prevent the rotation of the separator member from causing such an air flow, there is provided control means comprising in the present instance a baffle member 31 extending inwardly from the casing 22 at a point adjacent the bottom 32 of the separator member. This baffle is disposed in such proximity to the bottom of the separator member as to cause the escape of air from the chamber 25 to be properly limited or opposed. Because of the provision of this baffle, the air pressure within the chamber 25 may be so controlled that the pressure adjacent the opening 30 is substantially the same as the pressure in the chamber 24. As will be seen, the amount of this pressure will depend, other things being equal, upon the nearness of the baffle 31 to the lower surface 32 of the separator member, since this lower surface 32 will have a considerable centrifugal action which will tend to prevent the outflow of air from the chamber 25 at points in proximity to this surface. Other factors determining the amount of this pressure will be the extent of the portion of the lower surface of the bottom member 32 which is juxtaposed with the upper surface of the baffle and accordingly will be exerting an effective centrifugal action, the distance of the juxtaposed surfaces from the axis of the separator member, the relative roughness or smoothness of the surfaces, the distance between the flange 23 and the top of the separator member, etc. It will thus be seen that the baffle member and/or the bottom of the separator member may be designed to give a desired pressure in various types of centrifugal separators. The space between the baffle 31 and the rotatable-bottom may be just sufficient to provide a balanced pressure within the chamber 25 or may be sufficient to cause a slight flow through the clearance opening 30 in a desired direction. Preferably, the baffle should be adjustably mounted, as exemplified, so as to assure a proper action under different operating conditions. In the present instance, the baffle member 31 is provided with external screw threads 33 and the casing is provided with internal screw threads 34, so that the baffle may be moved nearer the bottom of the separator member, or further from it, to take care of varying conditions of operation. When the baffle is adjustable it may be designed to set up a desired range of pressures which will give satisfactory operation under different conditions. It will be apparent that the baffle member can be fairly near the bottom of the separator member without hindering the outflow of the heavy liquid thrown into the chamber 25, over the top of the baffle member and into the chamber 28 beneath it. The baffle member 31 is formed about its lower periphery with a series of recesses 35, and the casing is formed with an opening 36 through which a suitable tool may be inserted and worked to turn the baffle member and to adjust it to the proper position with respect to the bottom 32 of the separator member. During operation the hole is sealed and rotation of the baffle 31 prevented by means of a plug 37. As will be seen, the pressure within the chamber 25 can be very loosely controlled by the adjustment

of the baffle member, the threads 33 and 34 affording means enabling a substantially micro-adjustment of the baffle 31 to be obtained.

If desired, the bottom of the separator member may be extended outwardly to provide a somewhat greater surface above the baffle member. An arrangement of this sort is shown in Fig. 2, wherein the separator member 9a is provided with a bottom 32a having an outwardly-extending portion 38 beneath which an adjustable baffle 31a is threaded mounted.

Since certain changes may be made in the above construction and different embodiments of the invention could be made without departing from the scope thereof, it is intended that all matter contained in the above description or shown in the accompanying drawing shall be interrupted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. A centrifugal separator comprising a rotatable separator member, a stationary casing about said separator member, means including said casing providing upper and lower chambers for the reception of materials of different specific gravity, there being a gaseous medium in said chamber, said means being arranged to provide a clearance opening between said chambers to permit free rotation of the separator member, and baffle means adjustably mounted on the casing to substantially prevent a movement of said medium through said opening.

2. A centrifugal separator comprising a rotatable separator member, a stationary casing surrounding the separator member, a chamber between the casing and the periphery of the separator member, a clearance space between the casing and the separator member at the top of said chamber, means to discharge light liquid above said clearance space, means to deliver heavy liquid from said separator member to said chamber, and means extending inwardly from said casing in sufficiently close proximity to the bottom of the separator member so that the rotation of the separator member will build up a pressure in said chamber sufficient to desirably limit the passage of fluid into said chamber through said clearance space, said inwardly-extending means being spaced sufficiently from the bottom of the separator member to permit said heavy liquid to pass inwardly along said means so as to escape from said chamber.

3. A centrifugal separator comprising a rotatable separator member, a stationary casing surrounding the separator member, a chamber between the casing and the periphery of the separator member, a clearance space between the casing and the separator member at the top of said chamber, means to discharge light liquid above said clearance space, means to deliver heavy liquid from said separator member to said chamber, and means extending inwardly from said casing in sufficiently close proximity to the bottom of the separator member so that the rotation of the separator member will build up a pressure in said chamber sufficient to desirably limit the passage of fluid into said chamber through said clearance space, said clearance

space being nearer the axis of said separator member than the inner edge of said inwardly-extending means.

4. A centrifugal separator comprising a rotatable separator member, a stationary casing surrounding the separator member, a chamber between the casing and the periphery of the separator member, a clearance space between the casing and the separator member at the top of said chamber, means to discharge light liquid above said clearance space, means to deliver heavy liquid from said separator member to said chamber, and means extending inwardly from said casing beneath said chamber and adjacent the bottom of said separator member, the latter means being adjustable axially of the separator member to control the pressure built up within said chamber by the centrifugal action of the separator member.

5. A centrifugal separator comprising a rotatable separator member, a stationary casing surrounding the separator member, means to introduce into the separator member material to be separated, an upwardly-extending neck on the separator member arranged for the escape of light material from the separator member, a flange forming a part of said casing and extending inwardly adjacent said neck but out of contact therewith, means permitting the escape of heavy material from the separator member into the space between the separator member and said casing beneath said flange, and means extending inwardly from the casing in sufficiently close proximity to the bottom of the separator member so that the rotation of the separator member will build up a pressure in said space sufficient to substantially prevent the entrance of light material between said flange and said neck.

6. A centrifugal separator comprising a rotatable separator member, a stationary casing surrounding the separator member, means to introduce into the separator member material to be separated, an upwardly-extending neck on the separator member arranged for the escape of light material from the separator member, a flange forming a part of said casing and extending inwardly adjacent said neck but out of contact therewith, means permitting the escape of heavy material from the separator member into the space between the separator member and said casing beneath said flange, and adjustable means extending inwardly from said casing beneath said chamber and adjacent the bottom of said separator member, the latter means being adjustable to control the pressure built up within said space by the centrifugal action of the bottom of the separator member to desirably limit entrance of light material into said space.

7. A centrifugal separator comprising a rotatable separator member, a stationary casing surrounding the separator member, means to introduce into the separator member material to be separated, an upwardly-extending neck on the separator member arranged for the escape of a light liquid from the separator member, a flange extending inwardly from said casing and in proximity to but out of contact with said neck, means permitting the escape of heavy liquid from the separator member into the space between the separator member and the casing beneath said flange, and means threadedly connected with the casing and extending inwardly from said casing and beneath the separator member, the last-mentioned means being ad-

justable axially of the separator member so that it can be moved a sufficient distance from the bottom of the separator member so that the centrifugal action of the separator member will build up a pressure within said space, the inner edge of said last-mentioned means being disposed further from the axis of the separator member than the inner edge of said flange.

8. A centrifugal separator comprising a rotatable separator member the walls of which are turned inwardly and then upwardly adjacent its top to provide a neck, means to introduce adjacent the bottom of the separator member material to be separated, an annular baffle adjacent the inturned wall and spaced therefrom, means to conduct upwardly through said neck material passing inside said baffle, a casing surrounding said separator member, a flange extending inwardly from said casing and terminating in proximity to but out of contact with said neck, means to conduct out of said neck at a point beneath said flange material passing outside said baffle, and means extending inwardly from the casing and adjacent the bottom of the separator member, the latter means being adjustable axially of the separator member to control the pressure built up by the centrifugal action of the separator member within the space beneath said flange.

9. A centrifugal separator comprising the combination with an exterior housing, of a rotatable separator member within the housing, a stationary casing about the separator member between the said member and the housing and subdividing the space between the separator member and the exterior housing into an interior and an outside chamber, the interior chamber being adapted to receive heavier separated components issuing from the separator member while the outside chamber is adapted to receive lighter separated components issuing from a different portion of the separator member, the chambers being in communication with each other through an opening defining a clearance in which the separator member freely rotates, rotation of the separator member tending to draw air through the said opening from the outside chamber into the interior chamber, and substantially micro-adjustable means mounted on the said stationary casing and extending into proximity to the separator member for counteracting the passage of air through the said opening between the chambers, thereby preventing tendency of the separated components to become intermixed.

10. A centrifugal separator comprising the combination with an exterior housing, of a rotatable separator member within the housing, a stationary casing about the separator member between the said member and the housing and dividing the space between the separator member and the exterior housing into two chambers, one of which is adapted to receive heavy material delivered from the separator member, while the other chamber is adapted to receive light material delivered by the separator, a clearance space between the casing and the separator member, the said clearance defining an opening communicating between the chambers, means for discharging light material from the separator above the said clearance space into the chamber for light material, means for discharging heavy material from the separator to the chamber for heavy material, a baffle threadedly mounted on the stationary casing and extending inwardly from the stationary casing into sufficiently close prox-

imity to the bottom of the separator so that rotation of the separator will build up a pressure in the chamber receiving the heavy material sufficient to control, as desired, passage of fluid through the said clearance space, and means enabling adjustment of the said baffle relatively to the separator.

11. A centrifugal separator comprising the combination with an exterior housing, of a rotatable separator member within the housing, a stationary casing about the separator member between the said member and the housing and dividing the space between the separator member and the exterior housing into two chambers, one of which is adapted to receive heavy material delivered from the separator member, while the other chamber is adapted to receive light material delivered by the separator, a clearance space between the casing and the separator member, the said clearance defining an opening communicating between the chambers, means for discharging light material from the separator above the said clearance space into the chamber for light material, means for discharging heavy material from the separator to the chamber for heavy material, a baffle threadedly mounted on the stationary casing and extending inwardly from the stationary casing into sufficiently close proximity to the bottom of the separator so that rotation of the separator will build up a pressure in the chamber receiving the heavy material sufficient to control, as desired, passage of fluid through the clearance space, means enabling adjustment of the baffle relatively to the separator,

and instrumentalities for preventing turning of the baffle during rotation of the separator.

12. A centrifugal separator comprising the combination with an exterior housing, of a rotatable separator member within the housing, a stationary casing about the separator member between the said member and the housing and dividing the space between the separator member and the exterior housing into two chambers, one of which is adapted to receive heavy material delivered from the separator member, while the other chamber is adapted to receive light material delivered by the separator, a clearance space between the casing and the separator, the said clearance defining an opening communicating between the chambers, means for discharging light material from the separator above the said clearance space into the chamber for light material, means for discharging heavy material from the separator to the chamber for heavy material, a baffle threadedly mounted on the stationary casing and extending inwardly from the stationary casing into sufficiently close proximity to the bottom of the separator so that rotation of the separator will build up a pressure in the chamber receiving the heavy material sufficient to control, as desired, passage of fluid through the clearance space, means enabling adjustment of the baffle relatively to the separator, and instrumentalities for preventing turning of the baffle during rotation of the separator, the said instrumentalities comprising a recess in the baffle and a releasable locking pin extending into the said recess through the said exterior housing.
